UNITED STATES PATENT OFFICE

AUSTIN E. COFRIN, OF GREEN BAY, WISCONSIN

PAPER-MAKING MACHINE

Application filed July 14, 1927. Serial No. 205,814.

The invention relates to paper making machines of the Fourdrinier type and has as an object the provision of improved means to remove the water from the pulp upon the traveling wire.

A further object of the invention is the provision of means to remove water from the pulp upon the wire with less disturbance of the pulp than has resulted from former devices used for this purpose.

A further object of the invention is the provision of means of the character described which will enable the wire to be run at a much higher rate of speed than those used at present, when making the same class of paper.

A further object of the invention is the provision of means of the character described whereby the action of centrifugal force upon water upon the surface of the tube rolls tending to throw the water back through the wire with consequent disturbance of the forming sheet upon the wire is avoided.

A further object of the invention is the provision of a wire running at a speed such as to introduce the element of centrifugal force if used with normal smooth surfaced tube rolls and the use with wire run at such speeds of a tube roll which is of a foraminous character whereby the effect of centrifugal force referred to is avoided.

It is a further object of the invention to provide hollow tube rolls having perforated surfaces in alternation with bars, the combination being used with a Fourdrinier wire run at such speed as to introduce an objectionable action of centrifugal force, the use of such foraminous rolls and bars serving to prevent the objectionable effect of centrifugal force upon the forming sheet upon the wire.

Further objects will appear from the following description when read in connection with the accompanying drawings showing an illustrative embodiment of the invention, wherein:—

Figure 1 is a diagrammatical side elevation, partly in section, showing the device applied to the machine,

Fig. 2 is a plan view diagrammatical in character,

Figs. 3 and 4 are detail side elevations of modifications of roll and bar arrangements, and

Fig. 5 is a detail elevation partly broken away of one end of a foraminous roll and its support.

As shown, the machine embodies a Fourdrinier wire 10, a breast roll 11, couch rolls 12, and 13, a slice bar 14, and an apron 15 of the usual type. Suction boxes 16 and 17 are also shown.

One form of the mechanism provided by the present invention is shown in general at 18 and comprises means for positively revolving some of the tube rolls at speed at variance with the speed of the wire, also means for selectively placing into use the positively operated rolls or the idle rolls, or a combination of the two.

I have found that the usual tube rolls of the nature shown at 19, which are usually allowed to act as idlers in support of the wire, being driven by friction with the wire in the same direction as the travel of the wire, cause the water which travels with the wire, as a film upon its lower surface, to be forced upwardly by centrifugal force through the wire against the layer of stuff carried thereby, so as to cause a disturbance of the stuff and to delay its felting action.

In the usual practice, the water is found to be removed from the wire after passage of the wire over the tube roll under consideration rather than before the wire passes over the same, the surface friction of the water in contact with the roll, and the motion of the roll in the direction of the travel of the wire, causing the action referred to. In the usual practice referred to it was impossible to run the wire at high speeds since the action of centrifugal force to force the water carried by the smooth rolls up through the wire because at such speeds the formation of the sheet upon the wire was delayed and the resultant paper if run at such speeds would have a mushy character displaying when held to the light portions thinner than other portions thereof.

To prevent this action the present invention contemplates positive revolution of some or all of the tube rolls in the direction of the travel of the wire at a slower speed than the wire, or at a higher speed than the wire, or a positive revolution of the tube roll in a direction opposite to the travel of the wire. By the provision of the foraminous roll shown in the present application, the wire 10 may be driven at a much higher rate of speed even though the rolls are not positively driven but act as idle rolls since the water coming through the wire upon the side of the roll in the direction of travel of the wire is not supported throughout the surface of the roll but much of the water passes to the interior of the roll and is therefore not carried by the surface around to the side of the roll approaching the wire to be acted upon by such centrifugal force.

When any of the above expedients are adopted, the forcing of the film of water upward through the wire and the disturbance of the forming layer of pulp upon the wire 25 is materially avoided; also the water is removed from the wire with less disturbance, which renders possible an earlier formation of the paper, and if desired the use of a thicker solution of stock upon the wire, which 30 renders possible the use of a substantial increase in the speed of travel of the wire, and at the same time providing an improved product. By virtue of the same result it would be possible to use a shorter wire than 35 has heretofore been necessary to complete the formation of the paper.

To accomplish the function described, some or all of the tube rolls may be positively driven. As shown, each third roll is provided 40 with driving gears. The rolls 20, 21, and 22 are provided with bevel gears 23 in mesh with bevel gears 24, carried by a shaft 25, which shaft may be driven in either direction by means not shown.

45 To enable the selective operation of the driven rolls, or the idle rolls 19, each of the tube rolls shown is indicated as mounted upon an adjustable journal 26, which journals are supported in sockets 27 in supporting bars 50 28 by means of thumb screws 29. By manipulation of the screws 29 the idle rolls 19 may be each lowered out of contact with the wire and the driven rolls 20, 21, 22, brought into alignment and in contact with the wire, 55 or the idle rolls may be brought into operation and the driven rolls may be lowered. If desired for any purpose, both sets of rolls may be operated at the same time.

As shown in Fig. 3, means such as described in my Patent No. 1,623,526, granted April 5, 1927, for removing water from the under side of the wire 10 have been combined with the positively driven rolls above described and in Fig. 4 such means have been 60 65 combined with ordinary tube rolls with

means for bringing either or both into action at a particular time. As shown in Fig. 3, the bars for wiping off the water are shown at 30 mounted upon adjustable supports 26 which may be raised or lowered by means of screws 29. Therefore these bars may be used instead of the rolls 20, 21, 22, or in combination therewith.

The mounting of the bars 30 in Fig. 4 is similar to that in Fig. 3 but are alternated with ordinary idling tube rolls 19.

70 A further improvement is shown in Fig. 5. It has been discovered that any or all of the tube rolls provide unexpectedly good results if made with the surfaces perforated. There is therefore shown in Fig. 5 a roll 31 formed hollow and having its surface supplied with numerous perforations 32. When the positively driven rolls 20, 21, 22 are made as shown in Fig. 5, and driven so as to have a slippage between the roll and the wire 10, maximum results in removing the water from the under side of the wire are secured.

80 The speed at which the wire can be run with rolls of the usual smooth surface type 90 acting as idlers in the formation of tissue paper has been found to be substantially 300 to 400 feet per minute. By provision of foraminous rolls of the present invention even when driven at the speed of the wire or caused to run at such speed by friction with the wire and not positively driven, it is found possible to run the wire at a much higher rate of speed, the possible speed depending to some extent upon the nature of the paper which 95 is being manufactured.

100 Experiments already made seem to indicate that by the means disclosed a wire speed of 1000 feet per minute may be attained when making tissue paper.

105 Applicant is aware of patent to Bradbury No. 715,749 granted December 16, 1902, which was designed to allow water to drain through the roll upon the side of the roll which is approaching the wire but is not aware that this roll was ever used with a wire running at the speeds now contemplated nor with wire running at a speed which would introduce the bad effects of centrifugal action from the surfaces of the rolls. By use of the invention 110 above described, it is found possible to operate the wire at a substantial increase of speed and at the same time provide a superior product.

115 This application is filed as a substitute for and a continuation in part of my application Serial No. 92,856, filed March 6, 1926.

120 Minor changes may be made in the physical embodiment of the invention without departing from the spirit thereof within the 125 scope of the appended claims.

I claim:

1. In a Fourdrinier machine, in combination, a traveling wire, means to deliver pulp to said wire, tube rolls coating with said 130

wire, and means to positively drive at least one of said tube rolls in a direction and at a speed to increase the relative rate of speed of travel of the surfaces of the wire and roll.

5 2. In a Fourdrinier machine, in combination, a traveling wire, means to deliver pulp to said wire, tube rolls coating with said wire, and means to positively drive said tube rolls in a direction and at a speed to cause a slippage of the wire over the surface of the tube rolls.

10 15 3. In a Fourdrinier machine, in combination, a traveling wire, means to deliver pulp to said wire, tube rolls coating with said wire, and means to positively drive at least one of said rolls in a direction counter to that of the travel of the wire.

20 4. In a Fourdrinier machine, in combination, an idle tube roll, a positively driven tube roll, means to drive the latter to provide a slippage of the wire thereover, and means to selectively place either of said rolls into operation.

25 5. In a Fourdrinier machine, in combination, a Fourdrinier wire, tube rolls placed beneath said wire, bars placed beneath said wire adjacent to said tube rolls, and means for bringing either or both said bars and said rolls closely adjacent the under side of the wire for removing water therefrom.

30 35 6. A Fourdrinier machine comprising in combination, a Fourdrinier wire, a tube roll closely adjacent the under side thereof comprising a foraminous shell and means to positively drive said roll in a direction and at a rate of speed to provide slippage between the wire and the roll.

40 7. In a paper machine, a travelling carrier, table rolls for supporting the same, and means for driving some of the said table rolls at a different rate of travel than the rate of travel of said carrier.

In testimony whereof I affix my signature.
AUSTIN E. COFRIN.
